VENETIAN BLIND

Carl J. Delegard, Chicago, Ill., assignor to Joanna Textile Mills Company, Chicago, Ill., a corporation of Delaware.

Application February 17, 1944, Serial No. 522,743

4 Claims. (Cl. 160—173)

My invention relates to Venetian blinds and includes among its objects and advantages an improvement in the construction and interrelation of the various parts of such blinds, having particular bearing on the ease of removal and replacement for cleaning or repair purposes.

In the accompanying drawings:

Figure 1 is a front elevation, partly broken away, of a blind assembly according to the invention;

Figure 2 is an end elevation of the same assembly;

Figure 3 is a detail section on line 3—3 of Figure 1;

Figure 4 is a detail view as on line 4—4 of Figure 3, with the locking sleeve partly broken away;

Figure 5 is an edge elevation of the lower portion of Figure 4;

Figure 6 is a section on line 6—6 of Figure 4;

Figure 7 is a view similar to Figure 5 with the sleeve in section as on line 7—7 of Figure 6; and

Figure 8 is a section similar to Figure 3 indicating a previously employed construction.

In the embodiment of the invention selected for illustration the shade assembly includes the relatively fixed top rail 10, which is fixed to the window frame by any conventional or suitable means (not shown). The tiltable top rail 12 is supported from the rail 10 at the right end by the bracket 14 which includes a catch 16 for holding the pintle 18 in place on hook 20. At the left end I have indicated a housing 22 mounted on rail 10, which housing includes means engaging the plate 24 to support it, and conventional mechanism (not shown) actuated by the cord 26 for tilting the plate and rail.

The conventional ladder tapes, of which I have indicated two sets at 28 and 30, are suitably attached at their upper ends to the tilting rail 12 and at their lower ends to a similar bottom rail 32. The individual slats 34 are slotted at 36 to accommodate the lifting cords 38 and 40 and when the lifting cord and bottom rail 32 do not support them in closely stacked relationship they are supported by cleat strips 42 extending between ladder tapes closely adjacent to the slots 36 and staggered on the alternate sides so that the ladder strips will tend to hang straight at all times. The lifting cords 38 and 40 pass over suitable pulley or guide means indicated at 44, 46, and 48 in the top rail 10 and may constitute equal reaches of a single cord having a bight at 50 accessible to the user for adjusting the position of the bottom rail 32, which cord may be held in adjusted position by a conventional

locking mechanism indicated at 52. The ends of the rails 32 have pins 49 adapted to engage hooks 51 on holdown brackets 53, in case it is desired to restrain the blind from swinging, and rubber tips 55 to protect the adjacent casings.

The foregoing parts and assembly are conventional and per se constitute no part of the present invention, being included to facilitate a clear understanding of the invention and its relationship to parts described above.

The lower ends of the lifting cords 38 and 40 are each detachably connected to the bottom rail 32 by a quick-detachable connection positioned for relatively easy access without displacement of the ladder tapes. In Figures 3 to 7, inclusive, I have illustrated an aglet 54 attached to the lower end of the lifting cord and carrying a downwardly extending blade 56, the lower end of which is laterally notched at 58 with the lower right-hand corner of the notch curved down at 60 to receive a suitable metal eyelet or bight such as that of the staple 62 driven into the rail 32. To retain the parts against accidental disconnection I provide a sleeve 64 vertically slidable on blade 56 and limited in its downward movement by twisting the free end of the hook 66 at the bottom of the blade a little to one side as clearly indicated at 68 in Figures 5 and 7. I have indicated a rail 32 with a concave notch 80 in its upper face, of such proportions that member 62 need not project above the level of the body of the rail. Accordingly, the bottom slat 34 will rest on the rail without any accidental contact with the fastener 62 even if accidentally displaced in a longitudinal direction.

Referring now to Figure 8, I have previously employed a construction in which the rail 32' was formed with the through aperture at 82 and a counter-sink at 84. In such a construction the workman assembling these parts has to thread cord 38' through the hole 82 and tie a knot 81 in the end of the cord of a size that will enter counter-sink 84 and still carry the weight of the rail 32 and all the slats 34 without pulling 45 through hole 82. And after this is done, the ladder strip 30' is fastened to the bottom of the rail 32' and covers counter-sink 84. As the load on cord 38 is occasionally quite heavy and the size of the counter-sink 84 cannot be very large, such knotting calls for material skill in the part of the workman and even then the knot sometimes comes untied under the load or is so small that it works its way through hole 82. It will be apparent that with a construction according 50 to the invention the ladder strips may be assem-

bled with the rail 32 at any time, either before or after assembly of the lifting cords to the rail.

One of the main objections to Venetian blinds on the part of the user is that it is difficult to clean them thoroughly while assembled in place, and that removal for cleaning is a complicated and time-consuming undertaking. If the user disassembles an assembly cord to Figure 8 and subsequently puts it together again there is considerable risk that knot 81 will be too large and therefore unsightly or will come untied in service. And the removal and replacement of the ladder tapes is an additional nuisance.

With equipment according to the invention, either a service employee or a user can disconnect the lifting cords and then lift the upper rail 12 out of its supports, leaving only the permanent rail 10 and cords in place and detaching all the parts which most require cleaning still attached to each other so that they can readily be taken to a cleaning establishment, or to a repair shop for replacement of a damaged slat.

Without further elaboration, the foregoing will so fully explain the invention that others may readily adapt the same for use under various conditions of service.

I claim:

1. In a Venetian blind assembly of the type including a lifting rail and lifting cords having the lower ends connected to said lifting rail; quick-detachable connections between the lower ends of said cords and said rail; each connection including a bight carried by said rail; a hook carried by the lower end of the cord; and a sleeve telescoped over said hook; said sleeve having a downwardly opening notch at its lower end adapted to receive said bight, whereby accidental upward movement of said bight in said hook will cause said sleeve to ride up with said bight and still prevent said bight from becoming disengaged.

2. In a Venetian blind assembly of the type including a lifting rail and lifting cords having lower ends adapted to be connected to said lifting rail; quick detachable connections between the lower ends of said cord and said rail; each connection including hook means assembled to the lower end of the lifting cord; bight means assembled to the center of said lifting rail and adapted to engage said hook means; and retaining means in the nature of a vertically slideable sleeve assembled on said hook means to overlie said bight means when assembled and prevent accidental disengagement.

3. In a Venetian blind assembly of the type including a lifting rail and lifting cords having lower ends adapted to be connected to said lifting rail; quick detachable connections between the lower ends of said cord and said rail; each connection including bight means and hook means carried by said rail and cord; and gravity-held shield means when in lower position preventing disengagement of said hook and bight means.

4. In a Venetian blind assembly of the type including a lifting rail and lifting cords having lower ends adapted to be connected to said lifting rail; quick detachable connections between the lower ends of said cord and said rail; each connection including hook means assembled to the lower end of the lifting cord; bight means assembled to the center of said lifting rail and adapted to engage said hook means; retaining means in the nature of a vertically slideable sleeve assembled on said hook means to overlie said bight means when assembled and prevent accidental disengagement; and stop means carried by said hook means for preventing disassembly of said sleeve means when said detachable connection is disconnected.

CARL J. DELEGARD.
